ATTORNEY.

UNITED STATES PATENT OFFICE.

WILLIAM H. SAYRE, OF GLEN RIDGE, NEW JERSEY; WILLIAM HEYSHAM SAYRE, WILLIAM M. BEARD, AND ELIZABETH BARTHOLOMEW SAYRE EXECUTORS OF SAID WILLIAM H. SAYRE, DECEASED, ASSIGNEES TO AMERICAN ABRASIVE METALS COMPANY, A CORPORATION OF NEW YORK.

LAUNDER TROUGH.

Application filed February 14, 1920, Serial No. 358,700. Renewed May 17, 1924.

To all whom it may concern:

Be it known that I, WILLIAM H. SAYRE, a citizen of the United States, residing at Glen Ridge, in the county of Essex and State of New Jersey, have invented certain new and useful Improvements in Launder Troughs, of which the following is a specification, reference being had therein to the accompanying drawings.

This invention relates to troughs and like receptacles, such as launder troughs, employed more particularly in mining localities for conveying the mixture of water and ore, or rock fragments, slag and similar materials which it is necessary in mining operations to carry from one place to another. These troughs are frequently made of wood, but more frequently they are made in more durable and lasting form of iron and consist usually of a flat bottom with uprising edge walls or flanges thereby forming a flat open shallow trough. In practice it is found that the abrading action of the mineral substances carried in the stream flowing through the trough, causes rapid wear thereon and particularly on the bottom, with the result that the trough after a comparatively short period becomes unfit for further use. This necessitates frequent repairs or renewals which of course are attended with considerable expense, due to the cost of material, loss of time and interruption of the operations.

My invention aims to obviate this objection and the invention consists in providing the bottom of a metal trough with a series of inserts of a material harder than the metal of the bottom, and which are firmly embedded and fixedly held therein so as to be exposed on the surface of the bottom.

The inserts may be composed of different kinds of materials, and in different forms, and applied in different ways, but I prefer to employ them in the form of distinct lumps of hard abrasive material such as carborundum, alundum, corundum, or similar natural or artificial material in lump form and embedded in the bottom of the trough by casting the same in a suitable mold in which the lumps are properly disposed to be taken up by the casting and firmly held thereby and exposed on the surface of the bottom. It will be understood

that when the inserts are thus incorporated, the materials mentioned as composing the inserts are very hard and possess high resistant qualities against wear and are proof against impairment by the casting temperature of the metal of the trough. Consequently they are well adapted for the purposes of my invention, and can be conveniently and quickly incorporated in the trough bottom in the casting operation.

In the accompanying drawings:

Fig. 1 is a top plan view of a section of a launder trough having my invention embodied therein;

Fig. 2 is a sectional perspective view of the same;

Fig. 3 is a cross-section of a mold with the inserts disposed therein to be taken up by the metal of the casting in forming the trough.

Referring to the drawings:

A designates a section of a launder trough of which there will be a number placed end to end to constitute a continuous trough structure. The sections are made of cast iron with a flat bottom B and with upwardly extending edge walls or flanks C, so that when a number of them are placed end to end, a flat shallow trough will be formed suitable for receiving a stream of mixed water and ore, or rock fragments or slag and like materials handled in mining and similar operations.

In carrying out my invention I apply to the bottom of the trough so that they will be distributed over the area of the same, a series of inserts D, of a material which is harder than the metal of the trough, and I preferably dispose these inserts in rows, in the present instance longitudinal rows in which the individual inserts are spaced apart longitudinally of the trough, or in transverse rows in which the individual inserts are spaced apart transversely of the trough, the said inserts being firmly embedded and held in the bottom and exposed on the surface of the same.

The inserts may be formed of various different materials such as corundum, or carborundum, or alundum, or other hard natural or artificial material, but I prefer to employ distinct lumps of carborundum or alundum or corundum of substantial size as

distinguished from comminuted particles, and possessing an irregular formation so that they will be gripped by the material of the bottom in which they may be incorporated in the operation of casting the trough, these materials being very hard and possessing high resistant qualities against wear, and being of a character which will not be impaired or destroyed by the casting temperature of the metal. Thus disposed, the hard inserts will protect the bottom of the trough against rapid wear or deterioration by the abrasive action of the mineral substances of the stream flowing through the trough, with the result that the life of the trough will be greatly prolonged, and the necessity for frequent repairs, replacements and renewals and the consequent expense will be avoided.

By arranging the inserts in rows as above described, transverse and longitudinal intact portions E and F of the trough will be left, which will serve to maintain the strength and rigidity of the construction as a whole and will leave around the individual inserts, extensive and substantial areas of solid embedding metal.

Fig. 3 shows a mold suitable for casting the trough around the inserts. Here it will be seen that one surface G of the mold, that against which the bottom of the trough will be cast, has distributed thereover the inserts D slightly embedded in the sand of the mold so that in the casting operation, the metal forming the bottom of the casting will flow around the exposed portions of the inserts and they will become firmly embedded and gripped by the metal of the bottom as is shown in Fig. 2, and will in the finished casting be exposed on the surface of the bottom.

In the foregoing description and accompanying drawings, I have set forth my invention in the particular detailed form and construction which I prefer to adopt. It

will be understood, however, that these details may be variously changed and modified without departing from the limits of the invention; and further, it will be understood that the invention is not limited to any particular form or construction of the parts except in so far as such limitations are specified in the claims.

Having thus described my invention, what I claim is:

1. A launder trough composed of a metal body having in the bottom thereof a series of inserts of a material harder than the metal of the body, said inserts being firmly embedded in said bottom.

2. A launder trough composed of a metal body having in the bottom thereof, rows of wear resistant inserts composed of a material harder than the metal of the body.

3. A launder trough composed of a metal body having in the bottom thereof, rows of wear resistant inserts of a material harder than the metal of the body.

4. A launder trough composed of a metal body having inserts of carborundum embedded in the bottom.

5. A launder trough composed of a metal body having embedded in the bottom thereof, lumps of a material harder than the material of the body.

6. A launder trough composed of a metal body having embedded in the bottom thereof, distinct lumps of a harder material than the metal of the body, and which is proof against impairment by the casting temperature of the body metal.

7. As a new article of manufacture, a launder trough section composed of a metal body having a bottom and uprising edge flanges, and a series of inserts of a material harder than the metal of the body embedded in the bottom of the trough.

In testimony whereof, I have affixed my signature hereto.

WILLIAM H. SAYRE.
